UNITED STATES PATENT OFFICE.

OTTO GÄBEL, OF APOLDA, GERMANY, ASSIGNOR TO THE FIRM OF HUGO BURKHARDT,
OF APOLDA, GERMANY.

DOUBLE-RIB-WARP-KNITTING MACHINE.

1,078,914.

Specification of Letters Patent.

Patented Nov. 18, 1913.

Application filed February 10, 1913. Serial No. 747,356.

To all whom it may concern:

Be it known that I, Otto GÄBEL, residing at Apolda, in Germany, have invented certain new and useful Improvements in Double-Rib-Warp-Knitting Machines, of which the following is a specification.

This invention relates to knitting machines of the type comprising two opposite rows of needles for producing goods "right" 10 on both sides, and the object of the invention is to provide a machine of this class adapted for knitting tubular fabrics with open-work pattern, more particularly so-called "Hill" tubes for incandescence 15 mantles. It has heretofore been usual to use circular knitting machines for producing these mantles.

The invention is illustrated in the accompanying drawing, showing one form of 20 construction of the improved apparatus.

Figure 1 is a cross section taken through the holders of the thread presenting members of guides, and Fig. 2 is a side view showing one row of needles together with 25 guides coacting therewith. Fig. 3 is a diagram illustrating the production of tubular fabric by means of the machine.

In the drawing 3 and 3^a represent the front and rear needle bars, respectively, 3^b 30 and 3^c being the ordinary needles. The two bars are moved up and down alternately, the stitches being stripped off the needles on to the bars 24, 25 in well known manner.

It is essential to the production of open-work tubular fabric to use a larger number of guides than heretofore, arranged so that the machine can operate in the usual manner, and to this end the eyes of the warp guides must be brought together within 35 a small space. According to the invention this is effected by arranging that the guides on different holders lie between each other, either in the case of all the guides or some of them. In the example illustrated there are twelve guide holders, all 40 side by side, and two holders on each side of the machine are to work in the usual manner and coöperate in producing the side parts of the tube fabric, to be knitted flat.

50 The remaining eight holders with their guides knit the connecting parts, and these holders are arranged in pairs so that the guides of each pair lie with their ends in one line, side by side.

55 The two outer guides on each side of the machine are arranged in the usual manner;

in the drawing these guides are designated 5, 6 on one side, and 5^a, 6^a on the other side. The guides have holes for guiding the warp threads. The intermediate guides designated 7, 8, 9, 10 on one side and 7^a, 8^a, 9^a, 10^a on the other side, are arranged in pairs, so that the holes in each pair register, and 60 permanently retain this position. The relative movement of the rows of guides thus interposed between each other is allowed by the fact that only some of the guides (say 65 each eighth guide) are inserted, and that the longitudinal movement extends only over the space of, say, five guides. The 70 proportions can be varied according to the nature of the pattern.

It will be seen that the arrangement is symmetrical at opposite sides of the central line B—B of the machine. The essential feature is the arrangement of the inner pairs of guide holders so that the guides which they carry do not lie in separate rows side by side, but lie between one another. This space saving device enables a large 75 80 number of guides to work side by side for producing tubular goods.

The invention is not restricted to the use of any particular number of guides.

The production of tubular fabric is illustrated in Fig. 3. The guides 5 and 6 coact with the needles 3^b to form the front surface 1 and the guides 5^a, 6^a coact with the needles 3^c to produce the rear surface 2. In the diagram these two surfaces are shown side by 85 90 side, but they actually lie one behind the other. The connection of the two surfaces at the edges to produce a fabric having the same pattern as the two surface parts 1 and 2, is effected by means of the guides 7, 8, 9, 10 and 7^a, 8^a, 9^a, 10^a, which make the connections at the right hand side and left hand side respectively, the connecting 95 100 stitches being indicated in Fig. 3 by dotted lines.

The several guides work in the following manner: Guide 7 works from the fourth needle 3^b, counting from the right hand edge of the front surface, to the second needle, and thence to the first needle 3^c producing 105 the rear surface, and then in the same way back. Guide 8 works from the second needle (front surface) to the first, and thence to the third (rear surface), and back. Similar operations are performed by guides 7^a 110 and 8^a from the rear surface to the front surface; also by guides 9, 10 and 9^a, 10^a at

the left hand edge of the front surface and the opposite edge of the rear surface.

As will be seen by reference to the diagram, four guides are required on each side 5 for making the connections with exactly the same stitch formation as that of the surfaces; otherwise ridges are formed, which is undesirable in connection with incandescence mantles. It would be impracticable 10 to place all the guides side by side in the usual manner, because in this case the swing imparted to the carrier of the guide would be so great that the outer guide would become horizontal, and would be unable to lay 15 the thread over the needles 3^b, 3^c. With the overlapping arrangement shown, the swing need be no greater than if there were eight guides.

It has heretofore been proposed in connection with a so-called "Cotton's patents" 20

knitting machine to arrange two so-called "trick" bars at an angle so that when in action the ends of the thread guides overlap.

What I claim as my invention and desire to secure by Letters Patent of the United States is:—

In a double-rib warp knitting machine the combination with two rows of needles placed opposite each other, of warp guides arranged in pairs so that the ends of the 30 guides belonging to a pair lie side by side in a single row, for the purpose set forth.

In witness whereof I have signed this specification in the presence of two witnesses.

OTTO GÄBEL.
